(57) **CLAIM**

The ornamental design for a coating film transfer tool, as shown and described.

DESCRIPTION

FIG. 1 is a right side elevational view of a coating film transfer tool;

FIG. 2 is a left side elevational view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a front elevational view thereof with the disclaimed cap rotated to expose a head depicted in a position of use for convenience of illustration; and,

FIG. 8 is a front elevational view thereof; with a retaining portion rotated to depict a position of use for convenience of illustration.
